UNITED STATES PATENT OFFICE.

BEN S. CLARKSON AND WALTER E. CALDWELL, OF LOUISVILLE, KENTUCKY; SAID CALDWELL ASSIGNOR TO SAID CLARKSON.

TOBACCO HOGSHEAD.

Application filed May 22, 1923. Serial No. 640,754.

Our invention relates to hogsheads for packing and shipment of tobacco. It has for its object to form a hogshead of the kind mentioned formed in separable sections readily assembled when to be filled with the tobacco, the sections having interlocking members preventing one section from sliding on another and preventing the sections from collapsing when assembled, the sections being adapted to be readily separated one from the other when the tobacco is to be opened up for inspection in the warehouse, or at other times, and easily reassembled about the body of tobacco ready for further shipment. It has also for its purpose to provide a construction in which the lower head of the hogshead may be used as a moving platform or base for display of the tobacco when the sides of the hogshead are removed and replaced by other retaining walls permitting a part of the body of tobacco to be exposed for display purposes instead of using baskets of the type generally used for display purposes, this platform or base constituting one head of the hogshead when the display receptacle is removed and replaced by the sections constituting the shipping hogshead. It has further for its object to provide improved features of construction in various parts entering the general construction whereby material advantages are gained.

To the accomplishment of the foregoing and such other objects as may hereinafter appear the invention consists in the features hereinafter particularly described and then sought to be clearly defined by the claims, reference being had to the accompanying drawings forming a part hereof, and in which

Figure 1 is a perspective of a tobacco hogshead embodying our invention, parts being broken away for clearness of illustration;

Figure 2 is a front elevation of one of the sections of the hogshead;

Figure 3 is a rear elevation of one section;

Figure 4 is a bottom plan view of the lower head of the hogshead;

Figure 5 is a plan view of a two-part upper head for the hogshead;

Figure 6 is a fragmentary sectional view showing a manner of applying the lower head to the hogshead;

Figure 7 is a plan view of a top head for the hogshead showing holding prongs or spurs that may be used;

Fig. 8 is a side and a plan fragmentary view showing on an enlarged scale one of the holding prongs or spurs applied;

Figure 9 is a side view of a portion of the lower head with a caster applied;

Figure 10 is a side view of portions of two adjacent sections of the hogshead, showing on an enlarged scale one of the external battens with projecting ends;

Figure 11 is a perspective view of a display container, with portions broken away.

As illustrated in the drawings, the hogshead is composed of a number of separable sections 1, each section made up of a number of vertically disposed staves 2, the staves 70 of each section being secured together by upper external battens or hoops 3 and lower external battens or hoops 4, nailed or otherwise attached to the staves, and each having a projecting lip or tongue, 5, preferably beveled as illustrated at 6, so that when the sections are assembled to form the cylindrical body of the hogshead the lips or tongues of one section will lap over the stave of the adjoining section so as to maintain the sections 80 in an upright position, and the abutting beveled faces or edges of the tongues of adjacent sections will prevent vertical movement of one section relatively to the adjoining section. In other words, these projecting andlapping tongues or lips will tend to prevent lateral as well as longitudinal displacement of the various sections.

Each section is provided internally, near its lower end, with spaced apart liner-battens 90 or bars 7 and 8 which form a groove designed to receive the peripheral edge of the bottom or lower head of the hogshead, and serve to lock the head and sections together, the uppermost batten also serving to hold the head 95 against upward movement and the lower batten holding the head against the pressure of the contents of the hogshead. The bottom or lower head 9 of the hogshead is made up of a number of boards 10 held together and reinforced by battens 11 to the lower faces of which are attached foot-blocks 12 which serve as feet for the head to support it in position above the base or floor level so that the wall sections of the hogshead may be readily positioned for entrance of the periphery of the head into the groove formed by the two internal battens of the sections; and they also serve to take the weight of the hogshead and its contents from off the ends of the 110

staves and thus prevent injury to the sections in moving the hogshead over a floor or support. These foot-blocks also serve to receive readily detachable casters 13 the stems of which will fit in sockets 14 formed in the foot-blocks as indicated in Figure 9 of the drawing so that when the contents of the hogshead are to be displayed the container can be easily moved from one place to another as desired.

The top head of the hogshead 15 may be formed of a number of pieces as usual and the upper ends of the staves of the several sections chamfered and crozed as usual to receive the pieces of the head, and will be secured in place by battens 16 which may be in sections, or otherwise, as desired, and attached in the usual manner so as to secure the head in place. If desired the upper head 20 may be formed in two sections as illustrated in Figure 5 of the drawing, and the boards of each section attached together by battens 17 the adjacent edges of the battens of the sections being beveled as indicated at 18, Figure 5, so that when the two sections are assembled preparatory to being placed in the hogshead a proper alinement of the two will be obtained.

If preferred, an upper head of the form 30 shown in Figure 7 of the drawing may be used. In that form the individual boards of the head 19 are connected to one another by the battens 20, and the head, around its periphery, has attached to it by fastenings 21 any desired number of spurs 22, preferably 35 formed of spring metal and having their pointed ends projected upwardly and beyond the periphery of the head so that when the head is placed in position and pressed 40 downwardly the pointed ends of the spurs will pierce the staves of the sections and hold the head in place.

As additional means for locking the sections of the body to one another, a tongue 23 45 may be attached to one end stave near its lower end so as to project beyond the edge of the stave and engage with a keeper 24 attached to the lower part of the adjacent stave of the adjoining section as clearly indicated 50 in Figures 6 and 11 of the drawing, each section being provided along one edge with one of the tongues and along the other edge with one of the keepers so that when the sections are assembled these locks will aid in holding 55 the several sections firmly together.

It will be understood that when the several sections are assembled as described any desired number of hoops, bands, or wires 25 60 will encircle the body of the hogshead so as to prevent displacement of the sections in shipment or transport of the tobacco packed in the hogshead.

The construction described makes possible the ready removal of any one or more or all 65 of the sections for inspection of the packed to-

bacco as customary in the warehouse in making purchases of the tobacco or otherwise, and the sections may be readily reassembled or the separated section replaced so as to make the hogshead ready for further shipment or transport. In the construction of tobacco hogsheads as heretofore commonly made the taking apart and reassembling or replacement of the parts for inspection of the tobacco involves much time and labor and frequently results in such damage to the parts that much labor and expense is involved in restoring the hogshead to condition for further shipment. These serious objections are overcome under the present invention.

Also by forming the sections as described, the sections may be nested, one section in the other, for transport, and also for storage until the sections are to be assembled for reception of the tobacco to be packed.

In the leaf tobacco trade it is a common practice to remove a portion of the tobacco from the hogshead and place it in baskets for display. Under the present invention when the tobacco is to be put on display it is only necessary to remove the sections of the hogshead, leaving the tobacco resting on the bottom head of the hogshead, and replace the removed sections with other sections 26 similarly formed half the height, more or less, of the removed sections, for instance as illustrated in Figure 11 of the drawing, so that the tobacco will be freely exposed for display, the upper portion or layers of the tobacco being removed if desired. Then by applying 100 the casters to the display receptacle the display can be moved readily from place to place as desired. When shipment is to be made it is only necessary to replace the sections of the display receptacle with the original sections 105 and the tobacco is then ready for transport or shipment. The bottom head of the shipment hogshead serves as the bottom head of the display receptacle and when the removable sections of the hogshead have been replaced the hogshead may be filled with any tobacco that has been removed and the top head applied so as to put the filled hogshead in condition for shipment.

We have illustrated and described the preferred features of construction of the various parts but changes may be made therein and essential features of parts of the invention retained.

Having described our invention and set forth its merits what we claim is:

1. A tobacco hogshead, formed of separable sections, each section comprising a number of staves, transversely extending battens for each group section, the opposite ends of the battens of each section overlapping the adjacent group sections, the battens of one group being in alinement with the battens of the adjoining group, and the projecting portions of one set of battens overlapping cor- 130

responding portions of the other battens and serving to prevent one section moving longitudinally of the other in either direction, and internal battens attached to the lower portion of the sections and spaced apart to form a recess to receive the lower head of the hogshead.

2. A tobacco hogshead formed of separable sections, each section comprising a number of staves, transversely extending battens for each group section, the opposite ends of the battens of each section overlapping the adjacent group sections and one batten abutting endwise and vertically against the corresponding batten of the adjacent section to effect an interlocking engagement with the end of the adjacent batten, and internal battens attached to the lower portion of the sections and spaced apart to form a recess to receive the lower head of the hogshead.

3. A tobacco hogshead formed of separable sections, each section comprising a number of staves, transversely extending battens for each group section to secure the staves together, internal battens attached to the lower portion of the segments spaced apart to form a recess to receive a head to the hogshead, tongues projecting from a stave at one edge

of a section and a keeper from a stave at the other edge, said tongues and keepers of the several sections being located within the hogshead and in relation to each other that the tongue on one section will engage with the keeper on the adjacent section.

4. A head for tobacco hogsheads formed of sections, battens applied to each section in alinement one with the other, the adjacent ends of registering battens being inclined transversely of the battens, with the inclined ends in abutment and each extending across the dividing line between the sections.

5. A collapsible barrel formed of a plurality of sections, hoop sections secured to the barrel sections and having their opposite ends sheared on a bias and adapted to overlap the other barrel sections with the ends of the hoop sections abutting, and means for securing the barrel sections in assembled formation whereby the abutting edges of the hoop sections prevent vertical longitudinal movement of the barrel sections.

In testimony whereof we affix our signatures.

BEN S. CLARKSON.
WALTER E. CALDWELL.
